UNITED STATES PATENT OFFICE.

JAMES R. MACMILLAN, OF MENOMONEE, WISCONSIN.

PENHOLDER.

SPECIFICATION forming part of Letters Patent No. 503,151, dated August 15, 1893.

Application filed November 12, 1892. Serial No. 451,728. (No model.)

To all whom it may concern:

Be it known that I, JAMES R. MACMILLAN, of Menomonee, in the county of Dunn and State of Wisconsin, have invented certain new and useful Improvements in Penholders; and I do hereby declare that the following is a full, clear, and exact description thereof, reference being had to the accompanying drawings, and to the letters of reference marked thereon, which form a part of this specification.

This invention relates to appliances or implements known as pen-holders, which are designed to hold writing or marking pens and similar devices in proper position for effective use, and more particularly to that type or class of pen-holders which are so arranged as to permit of the detachment or expulsion of the pen from the pen-holder without the necessity of grasping the pen itself.

The objects of my invention are to produce a pen-holder of the type above stated, the operation of which shall be direct and positive and involve no changes in the relative longitudinal positions of the external parts of the holder.

To the above purposes, my invention consists in the novel features of construction and arrangement hereinafter described and claimed.

In order that my invention may be fully understood, I will proceed to describe it with reference to the accompanying drawings, in which—

Figure 1 is a side elevation of a pen-holder embodying my invention; the holding and expelling core or spindle being in retracted position. Fig. 2 is a central longitudinal section of the same, taken on the line 2—2 of Fig. 1. Fig. 3 is a sectional view similar to that of Fig. 2, but showing the holding and expelling spindle in projected position; said spindle and its screw-stem being shown in side elevation. Fig. 4 is a view in side elevation of the holding and expelling spindle and its screw-stem, detached from the other parts. Fig. 5 is a transverse vertical section of the pen-holder, taken on the line 5—5 of Fig. 1.

In the said drawings, A designates the stem or staff of the pen-holder, B the sleeve thereof, C the holding and expelling core or spin-

dle and D the screw-stem of said spindle. These parts are to be made of hard rubber, celluloid, wood, metal or any other suitable or preferred material; the staff or stem A and the sleeve B being collectively of such length as will permit of convenient manipulation of the holder in writing or marking. The stem or staff A is shown as gradually decreased in diameter from one end to another, but it may be of uniform diameter throughout if preferred and both the stem and the sleeve may be externally ornamented in any desired manner.

At one end, which, for convenience of description, will be called the lower end, the stem or staff A is provided with a longitudinal extension a, either formed integrally with the stem or staff as shown or suitably secured thereto. This extension a is of less diameter than that of the lower end of the stem or staff A and at its outer or lower end said extension is formed or otherwise provided with an external annular flange or shoulder a'. A longitudinal socket a² extends through the extension a and a suitable distance into the lower end of the stem or staff A, and said socket is internally screw-threaded, for a purpose hereinafter explained. Near its upper or inner end the sleeve B is formed with an internal transverse annular groove b, into which loosely fits the flange or shoulder a' of the extension a; the remaining upper or inner end portion of the sleeve B loosely surrounding the extension a, and the arrangement of the parts being such that the sleeve B can be rotated axially upon the stem A, by turning either the sleeve or the stem, but that the sleeve cannot be moved longitudinally of the stem or of the extension. The sleeve B is also formed with an annular transverse internal shoulder b' for arresting or limiting the retractive movement of the holding and expelling core or spindle, as hereinafter explained. The holding and expelling spindle C is, as to its middle or body portion, of cylindric form and of such external diameter as to fit closely within the sleeve B and yet permit the spindle to freely move longitudinally within the sleeve. At its inner or upper end the body portion of this spindle is shown as extending longitudinally inward and as reduced in diameter, as

at c , to enter the reduced inner or upper portion of the spindle B; an annular shoulder c' being thus formed at the point of juncture of the body portion of the spindle with the reduced portion or extension c , which shoulder comes at times into contact with the internal shoulder b' and thus limits the retractive movement of the spindle. Extending longitudinally inward from the upper extremity 5 of the extension c is an externally threaded screw-stem D, which is either formed integrally with the spindle C and its extension c , or suitably secured thereto, and which enters and works closely within the internally 10 screw-threaded socket a^2 in such manner that the stem or staff A may be turned axially upon the screw-stem in either direction and thus extend or protract the spindle, and also retract the same. At its outer end 15 the spindle C is formed with a head C' split longitudinally, as at c^2 , so as to permit the two portions of the head to impinge oppositely against the inner surface of the lower end of the sleeve B, when the spindle is retracted, and thus securely confine the end of the pen between the sleeve and the head. Rotation of the spindle within the sleeve is 20 prevented by a straight rib c^3 , which extends longitudinally of the spindle C and which 25 works freely within a straight longitudinal groove b^2 formed in the inner surface of the sleeve B. The sleeve B is shown as roughened externally to increase the user's grasp upon the pen-holder, and intermediate longitudinal plain portions are also shown upon the outer surface of the sleeve, but these features are obviously not essential to the invention. 30

The manner of using the pen-holder is as follows: Assuming the spindle to be retracted and a pen in position, as indicated in dotted lines in Fig. 1, and also that it is desired to detach the pen from the holder, the user grasps the sleeve with one hand and turns 40 the stem or staff A to the left with the other hand. This forces the spindle C outward within the sleeve B and projects the head C' out of the sleeve, as shown in Fig. 3, and expels the pen from the holder. A fresh pen 45 may now be inserted between the head C' and the lower end of the sleeve B, the end of the pen resting against the shoulder c^4 at the lower end of the spindle, and the stem or staff being rotated to the right, the head C' is 50 drawn inward and the pen is firmly clamped in position. The pen may, however, be inserted when the spindle C is retracted, by thrusting it between the side of the split head and the sleeve, in the same manner as in other 55 pen holders of the kind having a stationary split core within a tubular part or sleeve. 60

It is obvious that while I have shown the shoulder as formed upon the extension and the groove as formed in the sleeve, such con-

struction may be reversed; the shoulder being formed in the sleeve and the groove in the extension; also that while I have shown the rib as formed on the spindle and the groove as formed in the sleeve, this construction may also be reversed, the rib being formed in the sleeve and the groove in the spindle. 65 70

Having thus described my invention, what I claim as new therein, and desire to secure by Letters Patent, is—

1. A pen-holder, comprising a stem or staff 75 having an internally screw-threaded socket, a sleeve revoluble upon said stem or staff, but immovable thereon longitudinally and a spindle screw-threaded to engage the socket and having longitudinally movable and non-revoluble connection with the sleeve, substantially as described. 80

2. A pen-holder, comprising a stem or staff having a longitudinal and internally screw-threaded socket in its end and having also 85 an extension of said end, a sleeve embracing said extension so as to turn freely thereon, but immovable longitudinally thereon and a groove-and-shoulder connection between the sleeve and the extension, and a spindle having 90 longitudinally movable and non-revoluble connection with the sleeve and provided with an externally screw-threaded stem entering and working within the socket, substantially as set forth. 95

3. A pen-holder, comprising a stem or staff having a longitudinal and diametrically reduced extension at one end, an external shoulder carried by said extension, an internally screw-threaded longitudinal socket extending through the extension and into the stem or staff, a sleeve embracing the extension and its shoulder loosely so as to revolve thereon, a spindle having an externally threaded screw-stem engaging the socket, and 105 a rib-and-groove connection between the spindle and sleeve, to prevent relative rotation thereof, substantially as described. 100

4. A pen-holder, comprising a stem or staff having a longitudinal and diametrically reduced extension at one end, an external shoulder carried by said extension, an internally screw-threaded longitudinal socket extending through the extension and into the stem or staff, a sleeve embracing the extension and its shoulder so as to revolve thereon, a spindle having a head and an externally threaded screw-stem engaging the socket, and a rib-and-groove connection between the spindle and sleeve, to prevent relative rotation 115 thereof, substantially as described. 120

In testimony that I claim the foregoing as my invention I affix my signature in presence of two witnesses.

JAMES R. MACMILLAN.
